UNITED STATES PATENT OFFICE.

FREDERIC A. CHAPMAN, OF PHILADELPHIA, PENNSYLVANIA.

CUT-OUT BLOCK.

SPECIFICATION forming part of Letters Patent No. 539,725, dated May 21, 1895.

Application filed February 5, 1895. Serial No. 537,370. (No model.)

To all whom it may concern:

Be it known that I, FREDERIC A. CHAPMAN, a citizen of the United States, residing at Philadelphia, in the county of Philadelphia and 5 State of Pennsylvania, have invented certain new and useful Improvements in Cut-Out Blocks; and I do hereby declare the following to be a full, clear, and exact description of the invention, such as will enable others skilled 10 in the art to which it appertains to make and use the same.

This invention relates to an improvement in cut-out blocks.

The object of the invention is to produce a 15 cut-out block provided with simple, efficient, and durable means for effecting a connection between the main wires and the plug, and tap-wires and the fuse-wires, the connection being such as to permit of currents of high potential being passed through the plug without 20 any danger either of sparking, or any interference between the wires constituting the circuit or circuits.

Furthermore, the object is to produce a plug 25 in which the connections will be effectually shielded from contact with its casing, or with surrounding objects, preventing injury to the connections, and insuring their proper working when the parts are assembled.

Furthermore, the object is to produce a plug 30 constructed in such manner, that the respective wires of the circuit will be insulated from each other, thereby effectually preventing short circuiting of the current, and other accidents incidental to electrical connections.

Furthermore, the object is to produce a plug 35 which may be readily removed from its casing and transported to different points and quickly replaced in position.

Finally, the object is to produce a plug having 40 its parts so arranged that should the fuse-wire blow out, it may readily be replaced without the employment of skilled labor.

With these objects in view, the invention 45 consists in a cut-out having a plug provided on each of its sides with two chambers insulated from each other, one of the chambers having therein a contact-plate and a fuse-wire connected therewith, and the other a terminal 50 to which is attached the other end of the fuse-wire and one of the tap-wires, and a casing inclosing the plug and having contact-

plates. Furthermore, in the novel construction and combination of parts of a cut-out, as will be hereinafter fully described. 55

In the accompanying drawings, forming a part of this specification, and in which like letters of reference indicate corresponding parts, I have shown a convenient form of embodiment of two different ways in which the 60 invention may be carried into effect, and in these drawings Figure 1 is a view in elevation, partly in section, displaying in full lines the plug and its attached mechanism and in section the box or casing in which the plug is 65 housed. Fig. 2 is a view in side elevation of the plug, looking in the direction of the arrow, Fig. 1. Fig. 3 is a view similar to Fig. 1, showing a modified form of box contact-plate. Fig. 4 is a plan view, partly in section, 70 showing the box or casing provided with two sets of main wires supplying currents of different potentials, the plug being omitted, as that form shown in Fig. 1 may be employed in connection with this latter form of box. 75

Referring to the drawings, A designates the box or casing, which is adapted to be set in the floor, ceiling, or wall, as the requirements of the case may demand. The box, which may be constructed of any suitable or desired 80 material, is open at both ends, and is provided at its top with wings or flanges a, through which pass screws for holding the box in position.

To the inner surface of the ends of the box 85 are attached contact-plates a², which may be of any desired shape, but preferably that shown in Fig. 1, as presenting the best surfaces for contact with and release from the plug B, although the form shown in Fig. 3 90 may in some instances be preferred; and at the lower ends of the plates a² are binding-posts a³ for holding the main wires C.

When the box is to be seated in a floor, the flanges are let into the wood until the top of 95 the box is flush with the surrounding surface, and as the bottom of the box is open, it follows that any dirt or water which might enter thereto will immediately escape therefrom and thereby prevent any damage to the cut-out when the parts are assembled.

Should it be desired to remove the plug B permanently, or for a time, the box may be closed either by a dummy-plug or by a lid,

not shown, and in the case of the box being seated in the ceiling or wall, the dummy-plug may be stained, painted, or covered with paper, so as to cause it to resemble the surrounding surface, and thus prevent an unsightly appearance which would necessarily result if the box and plug projected beyond the ceiling or wall, as is the case with those in common use.

10 The plug B, to which reference has been made, is constructed of any suitable material, a non-conductor of electricity, and is provided in each of its sides with two chambers b , b^2 , which are of sufficient depth to allow their contained connections to lie wholly below the surface of the plug. As these chambers are the same on both sides of the plug, and as they perform the same function in both instances, a description of one will 20 serve for both.

15 The chamber b has, at its top, a side recess, b^3 , through which projects an arm or offset, d carried by the plug contact-plate D, the lower end of which plate projects below the bottom of the plug, and is slightly curved inward as at d^2 , to facilitate the insertion and removal of the plug. At a point near the bottom of the chamber, is an orifice b^4 which extends through to the chamber b^2 on the opposite side of the plug, it being understood that the chambers are so located on both sides of the plug that, on viewing it without turning it, the chamber b on one side will be in alignment with the chamber on the other side. 30 This is done to prevent crossing of the fuse-wires, as will be perfectly obvious.

25 The chamber b^2 has secured thereto a terminal b^5 , to one end of which is suitably connected one end of the tap wire E, the other tap-wire being correspondingly connected to the terminal in the chamber on the other side of the plug.

30 The terminals and offsets d are connected by fuse-wires F, which pass through the opening b^3 , and as shown in Fig. 1, are held in place by screws, b^6 and b^7 , respectively. This manner of securing the fuse-wires in place, is preferable to the ordinary method of soldering, as by the employment of screws, any person of ordinary ability may replace a fuse-wire should it blow out.

35 Should it be desired to employ the cut-out in connection with a power-plant, in addition to the electric lighting, the form of box shown in Fig. 4 will be employed, wherein 40 two circuits are connected with two sets of

contact-plates a^4 , one circuit furnishing, say, one hundred and ten volts, to be used for lighting, and the other two hundred and twenty volts to be used for power. In order 60 to employ the different circuits, it will only be necessary to insert the plug within the box in such manner as to bring the contact-plates d^2 , into engagement with the contact-plates a^4 , connecting with the circuit to be used. It 65 is to be understood that, if desired, the plug may be made circular in form, and still be made to perform its proper function.

Having thus described my invention, what I claim, and desire to secure by Letters Patent, is—

1. A cut-out having a plug provided on each of its two sides with two chambers insulated from each other, one of the chambers having therein a contact plate a fuse-wire 75 connected therewith, and the other a terminal to which is attached the other end of the fuse-wire and one of the tap-wires, and a casing inclosing the plug and having contact-plates, substantially as described.

2. A cut-out having a plug provided on each of its sides with two chambers insulated from each other, in one of which chambers is placed a terminal connected by a fuse-wire with the contact-plate in the chamber on the 85 opposite side of the plug and with the tap-wire, and, in the other chamber, a contact-plate and a fuse-wire connecting said plate with the terminal in the chamber in the opposite side of the plug, and a casing inclosing 90 the plug and having contact-plates, substantially as described.

3. A cut-out provided on opposite sides with chambers insulated from each other, contact-plates secured to the sides of the plug and 95 projecting below the bottom thereof, the upper ends of the said plates being provided each with an offset projecting into one of the chambers on each side of the plug, a terminal located in one of the chambers on each side 100 of the plug, fuse-wires connecting the offset of the contact plate on one side of the plug with the terminal on the opposite side thereof, and tap-wires connecting with the terminals, substantially as described.

105 In testimony whereof I affix my signature in presence of two witnesses.

FREDERIC A. CHAPMAN.
